UNITED STATES PATENT OFFICE.

MORRIS KOPPELMAN, OF NEW YORK, N. Y.

COAT-COLLAR.

No. 928,262.

Specification of Letters Patent.

Patented July 20, 1909.

Application filed March 9, 1909. Serial No. 482,334.

To all whom it may concern:

Be it known that I, MORRIS KOPPELMAN, a citizen of the United States, and a resident of the borough of Brooklyn, in the county of Kings, city and State of New York, have invented certain new and useful Improvements in Coat-Collars, of which the following is a specification.

My invention relates to collars for coats and similar garments, and the improvements wherein the invention resides relate to garments of the kind shown and described in my copending application No. 473,954, filed January 25, 1909. Its objects are, among others, to provide a collar of that description with means whereby the fold or crease will be formed on the inside when the collar is turned up and by which the extra width of the piece of material forming the turned down collar will be more definitely formed and the creeping or slipping of the material avoided, and whereby the said collar may be made to better retain its proper shape, and the thickness of the collar at the parts adjacent to where it joins the neck of the coat reduced to a minimum.

To this end it consists of the construction, combination and arrangement of parts hereinafter described and claimed and illustrated in the accompanying drawings.

In the said drawings Figure 1 is a back view of a collar embodying the improvements, in its turned-up position, with a portion of the cloth cut away to expose the interior of the collar. Fig. 2 is a vertical cross-section of the same in its turned-up position. Fig. 3 is a similar section showing the collar in its turned-down position.

The exterior of the collar is composed of two pieces of material E and D, the former forming the visible portion of the turned-down collar and the latter forming the outside of the turned-up collar. These two pieces of material—like the similar pieces of my original application—may be cut to form collars of various shapes or styles, and the interior parts cut accordingly, without departing from the invention. The lower edge of the piece E is secured to the lining F of the neck of the coat and the corresponding edge of the piece D is secured to the outside of the cloth of the neck. The two pieces may, however, be secured together at this point, if desired, and when the collar is applied to the unlined coat both pieces will be secured directly to the coat material.

The upper edges of the pieces D and E are secured together, and between them the upper edge of the interlining B is caught. This interlining is composed of stiff canvas, 60 haircloth or both, or some other stiff material. Its lower portion is entirely free and disconnected from the other parts of the collar, except through the strip A herein-after described, and its lower edge is preferably turned up and stitched at the back of the neck to give the interlining additional stiffness at this part. It extends from the upper or outer edge of the collar to the fold of the piece E so that when the 70 collar is turned up the hemmed edge of the interlining overhangs the fold or plait in the piece E and when the collar is turned down is within its upper edge. It is by means of this stiffening piece B, in connection with the connecting strip A arranged as herein set forth, that the shape of the collar is preserved in both positions and the plait or fold, which takes up the extra width of the piece E when the collar is turned 80 up, accurately formed and held in place.

The strip A is of flexible material and connects the lower edge of the piece D on the inside with the inner side of the stiffening interlining B at the lower part of said 85 interlining. It will be observed that the width of this strip A is much less than the width of the material of the piece E between its edges and that when the plait or fold I is formed in the piece E it takes up this 90 extra width. The action of the strip A, therefore, is to retain this plait or fold in its proper position and shape and to prevent the stiffening B, to which this upper edge 95 is secured, from working up and thus drawing the collar out of shape. When the collar is turned down the strip A permits the interlining to be reversed or inverted and prevents it while in this position from working down and thus causing the collar to 100 wrinkle and lose its shape.

The strip A is shown as stitched to the piece B at C, and this tends to cause the parts to more quickly take their proper positions when the collar is turned up, especially when light materials are used. It is not essential, however, and the collar will give entirely satisfactory results without it. This piece A is sewed inside the fold of the stiffening piece or interlining, and extends 110 along the edge of the portion which is next to the neck of the wearer when the collar is

turned down, being, however, secured to the interlining above its folded edge at the medial portion of the collar only, and for the remainder of its length being secured 5 to the extreme lower edge only. The interlining is also hemmed at its medial portion only. The object of this arrangement is to secure an accurate fold of the least thickness possible at the center, and to allow the parts 10 to adjust themselves to a certain extent on both sides of the middle. The piece A could, of course be made much shorter, and in fact might consist of only a short strip at the middle of the collar, without materially 15 affecting the operation of the various parts.

What I claim is:—

1. In a device of the character described the combination of two layers of material secured to the neck of the garment and forming 20 the outside of a collar, one of said layers being wider at its medial portion than the other, a lining of stiffer material extending from the outer and upper edges of the said layers to a point short of the inner edges of 25 the same, and a strip of more flexible material secured to the said lining at one edge and to the lower edge of one of the layers at its other edge, the width of the said lining and strip of flexible material being less than 30 the width of one of the layers.

2. In a device of the character described the combination of two layers of material secured to the neck of the garment and forming 35 the outside of a collar, one of said layers being wider at its medial portion than the other, a lining of stiffer material extending from the outer and upper edges of the said layers to a point short of the inner edges of the same, and a strip of more flexible material secured to the said lining at one edge and to the lower edge of one of the layers at its other edge, the width of the said lining and strip of flexible material being less than 40 the width of one of the layers, and a turned-up portion of the lining on its lower edge.

3. In a device of the character described the combination of two layers of material secured to the neck of the garment and forming 50 the outside of a collar, one of said layers being wider at its medial portion than the other, a lining of stiffer material extending from the upper and outer edges of the said layers to a point short of the inner edges of the same, and a strip of more flexible material secured to the said lining at one edge and to the lower edge of one of the layers at its other edge, the width of the said lining and strip of flexible material being less than 55 the width of one of the layers and a turned-up portion of the lining on its lower edge, the said flexible strip being secured to the lining at the upper part of the turned-up edge.

4. In a device of the character described the combination of two layers of material secured 65 to the neck of the garment and forming

the outside of a collar, one of said layers being wider at its medial portion than the other, a lining of stiffer material extending from the upper and outer edges of the said layers to a point short of the inner edges of 70 the same, and a strip of more flexible material secured to the said lining at one edge and to the lower edge of one of the layers at its other edge, the width of the said lining and strip of flexible material being less than the width of one of the layers and the said lining and flexible strip being disconnected from the said outer layers except at the upper edge of the former and the lower edge of the latter.

5. In a device of the character described the combination of two layers of material secured to the neck of the garment and forming 75 the outside of a collar, one of said layers being wider at its medial portion than the other, a lining of stiffer material extending from the upper and outer edges of the said layers to a point short of the inner edges of the same, and a strip of more flexible material secured to the said lining at one edge and to the lower edge of one of the layers at its 80 other edge, the width of the said lining and strip of flexible material being less than the width of one of the layers, and the said lining being disconnected from the said outer layers except along its upper edge.

6. In a device of the character described the combination of a plurality of strips of material secured to the neck of a garment along one edge and forming the sides of a collar, one of the said strips being of greater 100 width than the other at its medial portion, and the longitudinal edges of both being connected in alinement, a strip of less flexible material between the said two outside strips and secured thereto, said strip of less flexible 105 material being of lesser width medially than the narrower outer strip and having its part which is next to the neck of the garment disconnected from said outer strips at its medial portion and its inner edge coincident with 110 the fold of the collar when the said collar is turned down, and a strip of more flexible material secured near the inner edge of the said inside strip and also to the neck of the garment.

7. In a device of the character described the combination of a plurality of strips of material secured to the neck of a garment along one edge and forming the sides of a collar, one of the said strips being of greater 115 width than the other at its medial portion, and the longitudinal edges of both being connected in alinement, a strip of less flexible material between the two outside strips and secured thereto, said strip of less flexible material being of lesser width medially than the narrower outer strip and having its part which is next to the neck of the garment disconnected from the said outer strips and its 120 inner edge coincident with the fold of the col- 125 130

lar when the said collar is turned down, and a strip of more flexible material secured near the inner edge of the said inside strip and also to the neck of the garment and a connection 5 between the last named strip and the outer strip of greater width between the said neck of the garment and the inner strip.

Witness my hand this 17th day of February, 1909, at the city of New York, in the county and State of New York.

MORRIS KOPPELMAN.
